LOCK

Edward N. Jacobi, Milwaukee, Wis., assignor to
Briggs & Stratton Corporation, Milwaukee,
Wis., a corporation of Delaware

Application June 13, 1932, Serial No. 616,881

22 Claims. (Cl. 70—46)

This invention relates to locks and more particularly to a lock of the type commonly used in automobile switches.

It is an object of the present invention to produce a lock having a lock cylinder which is removable bodily from the mounting member. Another object of this invention is to provide a lock of the character described, wherein the lock cylinder is removably held assembled with its mounting member or casing by a novel interengaging connection between the locking bolt and the cylinder carried cam for actuating the bolt, which interengaging connection snaps into place upon the insertion of the cylinder.

More specifically, it is an object of this invention to provide means for removably holding the lock cylinder in the mounting member, which means may be released by holding the lock bolt in a depressed position and revolving the cylinder backwardly.

It is also an object of this invention to provide a novel construction for locks of the sliding cylinder type in which the energy of an expansion spring is released upon freeing of the locking bolt from its keeper recess, to move the lock cylinder axially and with it the element being controlled.

In this connection it is particularly an object of this invention to provide a lock cylinder of such construction that the front end portion exposed to view during the projection of the cylinder from the mounting member, presents a neat finished appearance while at the same time the cylinder is so designed as to facilitate manufacture by enabling the tumbler recesses to be cored out, and to maintain a short neck on the key.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a longitudinal cross section through a lock embodying this invention;

Figure 2 is a cross section on the line 2—2 of Fig. 1, looking in the direction of the arrows;

Figure 3 is a view similar to Fig. 2, but showing

the bolt in position to permit the removal of the cylinder;

Figure 4 is an end view of the lock cylinder per se;

Figure 5 is a view on the line 5—5 of Fig. 1, parts being shown in cross section to more clearly illustrate structural details;

Figure 6 is a top view of the lock assembly with parts broken away and in section and with the lock cylinder projected;

Figure 7 is a perspective view of the lock cylinder per se; and

Figure 8 is a perspective view of the mounting member per se.

Referring now more particularly to the accompanying drawings in which like numerals indicate like parts throughout the several views, the locking cylinder 10 is received in the bore of a mounting member or barrel 11 in which it is held against axial movement, but is free to rotate between locked and unlocked positions. The cylinder 10 and mounting member or barrel 11 are mounted for simultaneous sliding or axial movement within a casing 14.

The casing 14 is enclosed within an outer shell 80 or cover 15 which extends around the ends thereof and is preferably formed of chromium or some other similar metal readily polished, so as to present a pleasing appearance, especially at that portion thereof which is exposed to view when the lock is mounted for use.

The manner in which the assembled lock cylinder and mounting member are retained in the casing 14 and the manner in which removal of the lock assembly from the casing may be effected will be described in detail hereinafter.

The mounting member or barrel 11, as best illustrated in Figure 8, has its front end portion 12 reduced in diameter, with the juncture of the two diameters forming a shoulder 13. As is customary, the mounting member or barrel has diametrically opposite tumbler receiving grooves 29 and 30, the front end portions of which extend entirely through the wall thickness of the reduced forward end portion 12.

The lock cylinder 10 has an enlarged head or flange 22 at its front end of a diameter slightly less than the largest diameter of the mounting member or barrel and from this enlarged head or flange, a skirt 23 extends rearwardly to overlie the adjacent portion of the cylinder proper.

The internal diameter of the skirt 23 is slightly greater than the outside diameter of the reduced end portion of the mounting member to telescope over the same and permit the lock cylinder to be

inserted into the mounting member until the extreme front end of the mounting member engages the inner wall of the head or flange 22. The skirt 23 thus encircles the reduced front end 5 portion 12 of the mounting member or barrel and extends to substantially the shoulder 13.

The length of the skirt 23 is greater than the total sliding axial movement of the lock assembly in the casing so that the juncture between the 10 cylinder and its mounting member is never exposed to view.

The lock cylinder, as is customary has a series of locking tumblers 28 which are yieldably urged to project one end outwardly of the cylinder 15 proper into the tumbler receiving groove 29 when the cylinder is in its locked position.

The tumblers 28 are retractable into the cylinder to free the same for rotation upon the insertion of a proper key 31 into the cylinder, and 20 to obviate an objectionable long neck on the key 31, it is desirable that the series of tumblers 28 begin as near the front end of the lock as possible. Consequently the tumblers must extend forwardly of and beneath the skirt 23.

25 To avoid undue complications in the manufacture of the cylinder which is usually a die casting, and to permit the tumbler receiving grooves or recesses to be cored out in the usual manner, the annular skirt 23 is cut away as at 24 30 in line with the tumbler recesses.

Inasmuch as the lock assembly projects from the casing during unlocking a distance which would expose the cut-out portion 24 of the annular skirt 23, the front end of the cylinder is 35 encased in a cap 25 stamped from sheet metal of a thickness such that the outside diameter of the cap is substantially equal to the larger diameter of the mounting member or barrel 11.

Consequently, when the lock cylinder is assembled with the barrel, the entire unit or lock 40 assembly is of substantially the same diameter. The sheet metal cap 25 is held on the front end of the lock cylinder by having its end crimped over the inner end of the annular skirt as at 27. 45 Those portions of the inner end of the cap opposite the slots 24 are left uncrimped to avoid the objectionable appearance which would result if it were attempted to crimp the cap at these points.

50 The cap 25 has its outer surface highly polished to present a neat appearance and inasmuch as the cap is of the same diameter as the mounting member or barrel, only one finished member is necessary where two have usually been required. 55 A substantial saving in the cost of manufacturing the lock is thus effected.

The lock cylinder is held assembled with the mounting member or barrel 11 against axial movement by a novel interengaging connection 60 between the locking bolt 20 and the cam 33 projecting from the inner end of the cylinder. This interengaging connection is disengageable under certain conditions which will be hereinafter more fully described.

65 The locking bolt 20 is mounted for transverse sliding movement with respect to the mounting member within a transverse recess comprising a narrow rectangular opening 46 through the wall thickness of the mounting member or barrel at a 70 point in line with the tumbler receiving groove 29, and a wider rectangular opening 43 through the wall thickness diametrically opposite the opening 46 and in line with the tumbler groove 30.

75 The main stem 45 of the locking bolt is slidably received in the opening 46 and an enlarged

bifurcated end having spaced prongs 40 and 41 is disposed within the wider opening 43.

Between the prongs 40 and 41 is a projection 49 which centers one end of a spring 50 confined between the bolt and a cup member 18. This cup member is provided with an outstanding flange or rim 52 adapted to retain the cup member assembled in a port 53 in the mounting member or barrel.

The cup proper of the member 18 projects 85 through the port 53 beyond the outer cylindrical surface of the mounting member or barrel 11 into a longitudinal groove 55 in the casing 14 and its cover 15. The engagement of the cup member 18 in the longitudinal groove 55 holds the lock assembly 90 against turning in the casing 14 and also limits its linear motion.

When the lock assembly is in its retracted locked position as illustrated in Fig. 1, the main stem 45 of the lock bolt projects its end into an opening 47 formed in the casing 14, thus holding the lock assembly against linear movement until the lock cylinder is turned through the medium of the key to cause the cam 33 to retract the locking bolt against the action of the spring 50, 100 whereupon the lock assembly is freed for linear motion as constrained by the engagement of the cup shaped member 18 in the longitudinal groove 55.

105 The interengaging connection between the cam 33 and the lock bolt which as stated maintains the lock cylinder assembled with the mounting member will now be described.

The cam 33 is of novel construction and has two hook-like projections 37 and 38. These hook-like projections 37 and 38 overlie the inner face of the bolt at opposite ends of a recess 35 formed in the bolt.

110 Normally the action of the bolt spring 50 maintains the bolt and cam at such relative positions that the hook-like projections 37 and 38 are operatively engaged with the inner face of the bolt. In predetermined relative positions, which require retraction of the bolt beyond its normal retraction by the cam in unlocking, the recess 35 is large 115 enough and is of such shape as to permit the simultaneous disengagement of the hooks 37 and 38 from the bolt.

120 The condition is brought about by the fact that the locking bolt has a rectilinear movement transversely of the mounting member bore in which the lock cylinder turns, with the result that the space between the walls of the recess 35 in the locking bolt and the wall of the mounting member bore increases as the locking bolt is 125 drawn into retracted position. This is best illustrated in Fig. 3.

130 As there shown, the hook 38 moves out of operative engagement with the locking bolt when the cylinder is turned as stated. With the lock cylinder held in this position retraction or depression of the locking bolt beyond the degree to which it is moved by the cam, as by a tool 20a, disengages the bolt from the hook 37 without re-engaging it with the hook 38. In this position, 135 the lock cylinder may be readily withdrawn by an axial pull of the key 31.

140 The extreme inner end or nose of the cam 33 is beveled as at 37' to permit the interengaging connection between the cam and bolt to be effected merely by the insertion of the cylinder into the mounting member bore.

145 The disengagement of the interengaging connection between the lock cylinder cam and the locking bolt in view of the fact that the lock as- 150

sembly is enclosed within the casing 14, may be effected only when the lock assembly has been moved axially to its unlocking position at which position the active end of the locking bolt aligns with openings 67 and 68 in the casing 14 and cover 15.

These openings 67 and 68, being of less width than the adjacent end of the bolt, do not permit the bolt to extend therein, but merely afford access to the lock assembly through which a tool such as a screw driver end 20a shown in Fig. 3, may be inserted when the requirement for removal of the lock assembly arises.

The projection of the lock assembly axially from the casing is produced by the action of an expansive spring 61 confined between the innermost end of the casing and a disc 60 slidably received within the casing 14 and abutting the inner end of the mounting member or barrel 11. The disc 60 has the end of an actuating member or wire 65 secured thereto in any suitable manner as by clamping the end of the wire in a bore 63 by means of a set screw 66 threaded in transverse bore 64. The actuating wire leads to the element to be controlled through an armored cable as is customary.

From the foregoing description taken in connection with the accompanying drawings, it will be readily apparent to one skilled in the art, that this invention affords a novel construction for locks wherein a removable cylinder is desirable; that the interengaging connection between the cylinder and the locking bolt which serves to hold the locking cylinder assembled with the mounting member being located at the inner end of the cylinder and adapted to be engaged by merely snapping the cylinder in position, has many advantages, and that the construction of the front end of the cylinder which is exposed during the projection of the assembly during unlocking greatly reduces the cost of finishing and provides an exceptionally neat appearing construction.

What I claim as my invention is:

1. In a lock of the character described, a mounting member, a locking bolt in said mounting member, a lock cylinder mounted in said mounting member, a cam formed on said lock cylinder and engageable with said locking bolt to cause retraction thereof to an unlocked position, and a hook member extending past said bolt and being engaged over a shoulder thereon to maintain the lock cylinder assembled with the mounting member.

2. In a lock of the character described, a mounting member a bolt mounted in said mounting member for movement into and out of locked position, resilient means constantly urging said bolt into locked position, a lock cylinder mounted in said mounting member, a cam including an overhanging projection formed on the inner end of said lock cylinder and adapted to actuate said bolt, said projection extending past the bolt and being engaged over a shoulder thereon to retain the lock cylinder assembled within said mounting member.

3. In a lock of the character described, a casting having an aperture therein, a mounting member in said casing, a locking bolt carried by said mounting member and projectable therefrom into the aperture in said casing, a lock cylinder mounted for rotation in said mounting member, a cam including an overhanging projection on said lock cylinder, said cam being engageable with a portion of said bolt to actuate the same out of the

casing aperture, and said projection extending past said bolt and engaging the face of the bolt remote from said lock cylinder to retain the lock cylinder assembled with said mounting member.

4. In a lock of the character described, a casting having an aperture therein, a mounting member in said casing, a locking bolt carried by said mounting member and projectable therefrom into said aperture, a lock cylinder mounted for rotation in said mounting member, a cam, having an overhanging projection on the lock cylinder engageable with a portion of the bolt to move the bolt out of the casing aperture, said projection extending past the bolt and engaging the face of the bolt remote from the lock cylinder to maintain the lock cylinder assembled with in the mounting member, and means constantly urging the bolt to locked position with the projection engaging over the said face of the bolt.

5. In a lock of the character described, a casting having an aperture therein, a mounting member within the casing, a locking bolt carried by the mounting member and engageable in said aperture when in locked position, a lock cylinder with in said mounting member, a cam on said lock cylinder, an overhanging projection on said cam, said projection extending past the bolt and engaging the face of the bolt remote from the lock cylinder to maintain the lock cylinder assembled with the mounting member, and means constantly urging the locking bolt into engagement with the cam to maintain the overhanging projection of said cam engaged with said face of the bolt.

6. In a lock of the character described, a mounting member, a locking bolt mounted in the mounting member and projectable therefrom, a lock cylinder rotatably mounted in the mounting member, a cam formed on the inner face of the lock cylinder, an overhanging projection on the cam, said projection extending past the bolt and being engaged with the face of the bolt remote from the lock cylinder, and means constantly urging the bolt into a locked position with an edge thereof in engagement with said cam and the projection constantly in engagement with said face of the bolt, whereby the lock cylinder is maintained assembled in the mounting member.

7. In a lock of the character described, a casting having an aperture and a slot therein, a mounting member movable in the casing, a locking bolt carried by the mounting member and engageable in said aperture to hold the mounting member against movement, a guide member carried by the mounting member and engageable in said slot for guiding and limiting the movement of the mounting member, a lock cylinder in the mounting member, a cam formed on said lock cylinder and engageable with a portion of the bolt to actuate the bolt from engagement with the aperture, and an overhanging projection on the cam engageable with the inner face of the bolt to maintain the lock cylinder assembled in the mounting member.

8. In a lock of the character described, a casting having an aperture and a slot therein, a mounting member movable in the casing, a locking bolt mounted in said mounting member and engageable in the aperture to hold the mounting member in a locked position, a guide member carried by the mounting member and engageable in said slot for guiding and limiting the movement of the mounting member, a lock cylinder in the mounting member, a cam formed on said lock cylinder and engageable with a portion of the bolt to actuate the bolt from its

locked position, an overlying projection on said cam engageable with the inner face of the bolt to maintain the lock cylinder assembled with the mounting member, and means constantly urging the guide member into protracted position and said bolt into locking position.

9. In a lock of the character described, a casing having an aperture and a slot formed therein, a mounting member movable in the casing, a lock bolt having a recess therein mounted in the mounting member and projecting therefrom to engage the aperture in said casing to retain the mounting member in a locked position, a cup-shaped member projecting from the mounting member and engageable in said slot to guide the movement of the mounting member between locked and unlocked positions, a lock cylinder in the mounting member, means to releasably fix said lock cylinder relative to said mounting member including a cam formed on the inner end of the lock cylinder, an overhanging projection to the cam, said cam and said overhanging projection extending through the recess in the bolt, and means constantly urging the bolt to locked position with said overhanging projection engaging the inner surface of the bolt to maintain the lock cylinder assembled with the mounting member.

10. In a lock of the character described, a casing having an aperture and a slot formed therein, a mounting member movable in the casing, a lock bolt having a recess and mounted in the mounting member to project therefrom into engagement with said aperture to retain the mounting member in a locked position, a cup-shaped member projecting from the mounting member and engageable in said slot to guide the movement of the mounting member between locked and unlocked positions, a lock cylinder in the mounting member, means to releasably fix the lock cylinder relative to the mounting member including a cam formed on the inner end of the lock cylinder, an overhanging projection on the cam, said cam with said overhanging projection extending through the recess in said bolt, means constantly urging said bolt into locked position with said overhanging projection engaging the inner surface of the bolt to maintain said lock cylinder assembled with the mounting member, and a spring mounted in said cup-shaped member constantly urging said cup-shaped member and said lock bolt into protracted positions whereby the overhanging portion of the cam is maintained on the side of said bolt opposite said lock cylinder to retain the lock cylinder assembled with the mounting member.

11. In a lock of the character described, a mounting member, a lock bolt mounted in the mounting member, said bolt having a cut-away portion on one side thereof cooperating with the wall of said mounting member to form a variable dimensioned recess dependent in size on the position of the bolt in the mounting member, a lock cylinder in the mounting member, an eccentric cam on the lock cylinder including a stem and an overhanging projection on the outer end of said stem, the cam including said projection being projected through the recess with the overhanging projection contacting the face of the bolt remote from the cylinder, and means constantly urging the bolt into a position contacting the stem portion of the cam, whereby the overhanging projection is normally in operative engagement with the said face of the

bolt to maintain the lock cylinder assembled in the mounting member.

12. In a lock of the character described, a mounting member, a lock bolt mounted in the mounting member and adapted to releasably maintain the mounting member in a locked position, said bolt having a cut-away portion on one side thereof cooperating with the interior of the mounting member to form a variable sized aperture dependent in size upon the position of the bolt in the mounting member, a lock cylinder in the mounting member, a cam formed on the lock cylinder including a stem and an overhanging projection on said stem, means on said overhanging projection to retract the bolt into unlocked position to permit the passage of the cam through said aperture, and means constantly urging the cam into locked position with the edge of said cut-away portion engaging said stem under said projection whereby the lock cylinder is maintained assembled with said mounting member.

13. In a lock of the character described, a mounting member, a lock bolt mounted in the mounting member and adapted to releasably maintain the mounting member in locked position, said bolt having a cut-away portion on one side thereof cooperating with the interior of said mounting member to form a variable sized aperture dependent in size upon the position of the bolt in the mounting member, a lock cylinder in said mounting member, a cam formed on said lock cylinder including a stem and an overhanging projection on the stem, means on said overhanging projection to retract the bolt past its normal unlocked position to permit the passage of the cam through said aperture, means constantly urging said cam into locked position with the edge of the cut-away portion engaging the stem under the projection, whereby the lock cylinder is maintained assembled with said mounting member, and means whereby the locking bolt may be held in retracted position independent of the action of the cam to disassemble the lock cylinder from the mounting member.

14. In a lock, a casing, a mounting barrel in the casing, and a lock cylinder mounted within the mounting barrel and a part having a finished surface and completely covering that part of the mounting barrel not covered by the casing.

15. In a lock, a casing, a mounting barrel mounted for linear movement within the casing to project outwardly of the end of the casing, a lock cylinder within the mounting barrel, and an inwardly projecting skirt having a finished outer surface carried by the cylinder and covering the mounting barrel end portion projectable from the casing end.

16. In a lock, a casing, a lock assembly within the casing comprising a mounting barrel and a lock cylinder therein, said lock assembly being projectable from one end of the casing, and a single member having a finished surface encasing the lock assembly portion projectable from the casing.

17. In a lock of the character described, a casing a lock assembly having linear movement within the casing and having a portion projectable from the casing, said lock assembly comprising a mounting barrel and a lock cylinder received therein, and means carried by the lock cylinder and extended rearwardly thereof to overlie the adjacent end portion of the mounting barrel, said means extending rearwardly a distance greater than the total projection of the lock assembly from the casing, whereby the juncture between

the lock cylinder and mounting barrel remains covered by the casing during the projection of the lock assembly therefrom.

18. In a lock of the character described, a casing, a lock assembly having linear movement within the casing and having a portion projectable from the casing, said lock assembly comprising a mounting barrel and a lock cylinder received therein, and means carried by the lock cylinder and extending rearwardly thereof to overlie the adjacent end portion of the mounting barrel, said means extending rearwardly a distance greater than the extent of the projection of the lock assembly from the casing, whereby the juncture between the lock cylinder and mounting barrel remains covered by the casing during the projection of the lock assembly therefrom, and said means having its surface exposed to view when the lock assembly is projected from the casing neatly finished.

19. In a lock of the character described, a casing, a lock assembly having linear motion within the casing and projectable from the casing, said lock assembly comprising a mounting barrel and a lock cylinder received in the mounting barrel, the lock cylinder being inserted into the mounting barrel a distance to position the outer end of the mounting barrel closely adjacent the front end of the lock cylinder, a series of key operable locking tumblers carried by the lock cylinder and engageable with a recess in the mounting barrel to restrain the lock cylinder against rotation, said series of locking tumblers beginning substantially in line with the outer end of the mounting barrel to be disposed closely adjacent the front end of the lock cylinder and thus obviate a long neck on the key used to retract the tumblers, and an annular wall extended from the front end of the lock cylinder to overlie the adjacent front end portion of the mounting barrel and certain of the locking tumblers, said annular wall being cut away at its portions overlying the tumblers to facilitate manufacture of the lock cylinder, and a sheet metal cap engaged over the front end portion of the lock cylinder and having a cylindrical wall extending rearwardly over the annular wall to cover the cut-away portions on the annular wall and afford a neat finished appearance for the entire portion of the lock assembly projected from the casing.

20. In a lock of the character described, a casing, a lock assembly having linear motion within the casing and projectable from the casing, said

lock assembly comprising a mounting barrel and a lock cylinder received in the mounting barrel, the lock cylinder being inserted into the mounting barrel a distance to position the outer end of the mounting barrel closely adjacent the front end of the lock cylinder, a series of key operable locking tumblers carried by the lock cylinder and engageable with a recess in the mounting barrel to restrain the lock cylinder against rotation, said series of locking tumblers beginning substantially in line with the outer end of the mounting barrel to be disposed closely adjacent the front end of the lock cylinder and thus obviate a long neck on the key used to retract the tumblers, an annular wall extended from the front end of the lock cylinder to overlie the adjacent front end portion of the mounting barrel and certain of the locking tumblers, said annular wall being cut away at its portions overlying the tumblers to facilitate manufacture of the lock cylinder, and a sheet metal cap engaged over the front end portion of the lock cylinder and having a cylindrical wall extending rearwardly over the annular wall to cover the cut-away portions on the annular wall and afford a neat finished appearance for the entire portion of the lock assembly projected from the casing.

21. In a lock of the character described, a mounting member, a lock cylinder rotatable therein, a spring pressed locking bolt carried by the mounting member and movable transversely of the axis of the lock cylinder, said spring pressed locking bolt having a recess, a cam on the lock cylinder engageable in the recess to retract the locking bolt, and hook means on the cam engageable with the locking bolt to retain the lock cylinder in the mounting member, said locking bolt recess and the cam being of such relative shapes that the urging means of the bolt normally maintains the hook means engaged with the bolt and disengagement is possible when the bolt and cam are in predetermined relative positions.

22. In a lock, a casing, a mounting barrel in the casing, and a lock cylinder to turn within the mounting barrel and having an externally finished inward extension cooperating with the casing to cover the mounting barrel.
